UNITED STATES PATENT OFFICE

HENRY O. GIRARD, OF NASHUA, NEW HAMPSHIRE

DESIGN FOR A TABLE

Application filed March 9, 1929. Serial No. 30,417. Term of patent 7 years.

To all whom it may concern:

Be it known that I HENRY O. GIRARD, a citizen of the United States, residing at Nashua, in the county of Hillsborough and State of New Hampshire, have invented a new, original and ornamental Design for a Table, of which the following is a specification, reference being had to the accompanying drawing, forming part thereof.

In the drawings, Figure 1 represents a front perspective view of a table, showing my new design. Figure 2 represents an elevation view of the table as seen from the side.

The rear of the table is identical with the front.

I claim:

The ornamental design for a table, as shown and described.

HENRY O. GIRARD.
